Primary Examiner — Rosemary K Tarcza*(74) Attorney, Agent, or Firm* — Nitin Kaushik(57) **CLAIM**

The ornamental design for a foldable 3-in-1 wireless charger, substantially as shown and described.

DESCRIPTION

FIG. 1 is a top, front and left side perspective view of a foldable 3-in-1 wireless charger showing our new design; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; FIG. 7 is a bottom plan view thereof; FIG. 8 is a perspective view of its unfolded state; FIG. 9 is a perspective view of its unfolded state; and, FIG. 10 is a perspective view of its unfolded state thereof. The broken lines in the drawings illustrate the portions of the foldable 3-in-1 wireless charger, which form no part of the claimed design.
